(57) **CLAIM**

The ornamental design for a trailer hitch cover, as shown and described.

DESCRIPTION

FIG. 1 is a perspective view of a trailer hitch cover, showing my new design; and,

FIG. 2 is a section view taken along line 2—2 in FIG. 1. The broken line showing of environment is for illustrative purposes only and forms no part of the claimed design.

1 Claim, 2 Drawing Sheets

FIG. 2
